UNITED STATES PATENT OFFICE.

GEORGE H. MILLER, OF PAWTUCKET, ASSIGNOR OF ONE-HALF TO SAMUEL E. WOOD, OF LINCOLN, RHODE ISLAND.

COMBINED BOLSTER AND STEP FOR SPINDLES OF SPINNING-MACHINES.

SPECIFICATION forming part of Letters Patent No. 244,644, dated July 19, 1881.

Application filed April 18, 1881. (No model.)

To all whom it may concern:

Be it known that I, GEORGE H. MILLER, of Pawtucket, in the county of Providence and State of Rhode Island, have invented a new and useful Improvement in Combined Bolsters and Steps for Spindles of Spinning and Twisting Machines; and I hereby declare that the following is a full, clear, and exact description of the same, reference being had to the accompanying drawings, forming part of this specification.

This invention has reference to an improvement in the step and bolster for spindles of spinning and twisting machines; and it consists in the peculiar and novel arrangement by means of which the step and bolster are united and held against rotation, as will be more fully set forth hereinafter.

Figure 1 is a sectional view of my improved step and bolster, shown in connection with a spindle provided with a sleeve-whirl and a standard or bolster-case, constructed to be secured to the rail of a spinning or twisting machine. Fig. 2 is a vertical sectional view of my improved step and bolster. Fig. 3 is a horizontal sectional view of the same, showing the pins by which the bolster and step are secured.

In spindles as heretofore constructed, in which the step and bolster are united by means of a woven tube extending over both, the bolster and woven tube must fit loosely into the case or tube in which they are held, so that the spindle and bolster may adjust themselves to the true center of the bobbin carried on the spindle. In practice two difficulties have become manifest—viz: in starting the spinning-frames provided with such spindles, or when the lubrication is imperfect, the bolster is liable to rotate with the spindle, and will cut or wear the woven tube, particularly at the junction of the bolster with the step, as the step is less liable to rotate than the bolster; then, the continuous change in the position of the bolster strains, tears, and breaks the woven tube at the joint between the step and the bolster. When the woven tube is thus torn it becomes difficult to remove the step from the tube and replace the old woven tube by another. To obviate these difficulties, and also to allow the

step to yield with the bolster to the effort of the spindle to adjust itself is the object of this invention.

In the drawings, *a* represents the spindle; *b*, the sleeve-whirl secured to the spindle. *c* is the bolster case or standard into which the bolster and step are placed. *d* is a flange which rests on the bolster or spindle rail, and *e* is a nut with which the bolster case or standard is secured to the rail of the spinning-machine. All the parts so far described are used in spinning-machine spindles of this class.

The step and bolster consist of the tube *f*, in which the step *g* is secured by means of a pin passing transversely through the step *g* near its lower end, and through the tube *f*, so as to form a pivotal connection. In place of the tube *f*, a block of metal, in which a hole is bored to receive the step *g*, may be used.

h is the bolster-tube connected with the step *g*; also, by means of a pin passing transversely through the step and the tube at right angles to the pin in the lower end of the step, so as to form a gimbal or universal joint and allow the bolster-tube to adjust itself in any direction; and to allow of this free adjustment the step *g* is of less diameter than the holes in *f* and *h*.

The piece *f* is of larger diameter than the bolster *h*, and is made to fit tightly into the bolster-case *c*, so that it is firmly held against rotation, and as the bolster *h* is secured to the step *g* and the step to the piece *f* the bolster, while free to yield to the spindle, cannot rotate with the same.

The woven tube *i* forms a yielding packing between the bolster *h* and the bolster-tube *c*; but this tube *i* extends only to the lower end of the bolster *h*, and is not affected by the motion of the bolster.

As the step is pivotally connected with the piece *f* it will yield with the bolster and spindle, particularly when the pin forming the pivot is loosely fitted, and thus the bearing of the spindle on one side of the step is prevented; and, as the bolster and step are secured together, the whole can be more readily withdrawn when it becomes necessary to renew the elastic packing *i*.

Having thus described my invention, I claim as new and desire to secure by Letters Patent—

1. The combination, with the bolster-tube *c*, and the spindle *a*, of the piece *f*, the step *g*, and tube *h*, connected together by gimbal-pins, as and for the purpose described.
- 5 2. The combination, with the bolster-case *c*, of the piece *f*, secured in the same, the bolster *h*, and the step *g*, secured by gimbal-pins to the bolster *h* and piece *f*, so as to make a universal joint, as described.
- 10 3. The combination, with the bolster-tube *h*,

the piece *f*, of larger diameter than the bolster-tube, and step *g*, secured together by means of pins, so as to form a yielding connection, of the elastic packing *i*, the whole adapted to be placed into a bolster-case and form a yielding bearing for a spindle, as described. 15
